UNITED STATES PATENT OFFICE.

EMERY S. SIMCOX AND CHARLES LANKESTER WATERS, OF COSHOCOTON, OHIO.

PAPER SUPPORTING AND DISPENSING BRACKET.

Application filed April 15, 1921. Serial No. 461,551.

To all whom it may concern:

Be it known that EMERY S. SIMCOX and CHARLES L. WATERS, citizens of the United States, residing at Coshocton, in the county 5 of Coshocton and State of Ohio, have invented certain new and useful Improvements in Paper Supporting and Dispensing Brackets, of which the following is a specification.

This invention relates to an improved sup-

10 porting bracket primarily adapted for use in supporting for dispensing purposes various rolled materials, such, for example, as ordinary toilet paper, paper towels or other similar spirally wound materials.

15 The primary object of the invention resides in the provision of a supporting bracket of this character wherein is provided a novel and improved mounting for effecting the rotatable support of the paper carrying drum, 20 in order that said drum will be permitted to rotate to a predetermined extent, when paper is being withdrawn therefrom, the means provided for arresting the rotation of the drum serving to permit of a regulated length 25 of paper to be removed from the roll carried by the drum, and in this manner the said bracket serves to provide a regulated delivery of such paper and to eliminate all waste in the dispensing thereof.

30 With these and other objects in view, as will appear as the description proceeds, the invention accordingly consists in the novel features of construction, combinations of elements and arrangements of parts, herein- 35 after to be fully described and pointed out in the appended claim.

In the accompanying drawing, forming a part of this specification, and in which similar characters of reference denote like and 40 corresponding parts throughout the several views thereof:

Figure 1 is a perspective view of the improved bracket comprising the present invention,

45 Figure 2 is a horizontal sectional view taken through the bracket and disclosing more particularly the apparatus for effecting the rotatable support of the roll carrying drum or core,

50 Figure 3 is a vertical transverse sectional view taken along the line 3-3 of Figure 2,

Figure 4 is a perspective view of one of the rack members, and

55 Figure 5 is a similar view of one of the core journaling pinions.

Referring more particularly to the de-

tails of the invention, the numeral 1 designates the improved bracket comprising the present invention in its entirety. The said bracket in this instance is formed to include 60 a vertically disclosed rear wall 2, and forwardly projecting parallel side arms 3. It will be understood that the side arms 3 may be spaced a sufficient distance to receive a paper roll 4 of any standard size, and that 65 the dimensions of the bracket may be varied to adapt the same to the size of the material to be dispensed therefrom.

The roll 4 is adapted to be axially supported by means of a longitudinally extending core or drum 5, which is of a longitudinally tapered nature and is capable of being removably positioned through the center of the roll 4 in the ordinary manner, the tapered construction of the core serving to 70 permit the same to rotate in unison with the roll when paper is being withdrawn from the latter.

To mount the core, use is made of a pair 75 of pinions 6, which are disposed to project longitudinally and axially from the ends of the core. Usually the core is formed from wood, and therefore the inner ends of the pinions are of chisel formation, in order 80 that the same may be driven into the ends 85 of the core. The inner faces of the arms 3 are provided with registering metallic rack members 7, which are formed to include elongated slots 8 having rack teeth 9 formed on the lower walls thereof, the said teeth 9 being disposed to mesh with the teeth of the pinions 6. It will be observed that the 90 rack members are inclined as regards the horizontal, the inner ends of said rack members being situated below the longitudinal 95 axis of the core 5, and the outer ends thereof above said axis.

It will therefore be manifest that by the action of gravity the pinions 6 will occupy normally positions of operation in the lowest parts of the slots 8, so that 100 when paper is withdrawn from the roll 4, the latter will be rotated by the manual act of withdrawing the paper. This rotation of the roll causes corresponding rotary movement to be imparted to the core 5 and its 105 pinion 6, thus causing the said pinions to advance along the rack teeth 9 toward the highest portions of the slots 8. This serves to enable paper to be withdrawn from the roll, and the length of such paper will be 110 regulated by the length of the slots 8, since it will be manifest that when the pinions 6

reach the uppermost parts of the slots 8, rotation on the part of the core 5 will be arrested, thus causing the sheet of paper to be severed from the body of the roll 4 by 5 reason of the perforations within such paper and the continued application of the manually exerted pressure thereon. When the paper has been severed, the roll 4 is released, thus permitting the pinions 6, by the operation of gravity, to again rotate toward 10 the lowermost portions of the slots 8. This rearward rotation on the part of the roll permits a sufficient amount of the paper at the outer end thereof to drop downwardly 15 in order that the said end of the roll may be subsequently gripped to effect its convenient withdrawal. One of the rack members 7 has its lower wall hinged as at 20 to the body of the rack member, in order that by rocking the rack member about the pivot or hinge 10, it will be possible to readily remove the core 5 to permit of the removal or substitution of a roll 4 thereon. The hinged wall may be maintained in its 25 locked position by means of a resilient lip 11.

In view of the foregoing, it will be apparent that the present invention provides a simple yet efficient bracket adapted for the support of paper rolls, and wherein an 30 improved structure obtains for the purpose of automatically regulating the manual dis-

pensing of paper withdrawn from said rolls. The apparatus is of an extremely simple nature and by reason of its construction the same will be maintained at all times in an operative condition and free from mechanical disorder. It will be particularly observed that the construction eliminates the use of springs, ratchets or other delicate and fragile mechanisms which are very likely to 40 become readily out of order. By reason of the simplicity of the bracket, the latter may be manufactured and sold at a very reasonable cost. 45

What is claimed is:

A paper supporting and dispensing bracket comprising a pair of spaced side arms capable of supporting for rotation therebetween a paper roll, upwardly and forwardly inclined rack members secured to 50 said sides, a paper supporting core, pinions provided upon the ends of said core and disposed to operate over the teeth of said rack members, one of said rack members being pivotally connected with the associated 55 arm to permit the removal of said core from said bracket.

In testimony whereof we affix our signatures.

EMERY S. SIMCOX.

CHARLES LANKESTER WATERS.
